UNITED STATES PATENT OFFICE

THOMAS E. LANDVOIGT, OF WESTMONT, JOHNSTOWN, PENNSYLVANIA, ASSIGNOR TO NATIONAL RADIATOR CORPORATION, OF JOHNSTOWN, PENNSYLVANIA, A CORPORATION OF DELAWARE

HEATER CONSTRUCTION

Application filed September 18, 1928. Serial No. 306,642.

My invention relates to an improvement in heater constructions, and more particularly to heaters for small buildings such as houses and stores.

5 In heating isolated buildings of relatively small size, such as stores and residences, hot water and low pressure steam systems are extensively utilized. Such systems comprise a heater for heating the water or generating 10 steam, as may be desired. The heater is usually located in the basement or an outside room of the building. From the heater, pipes carry the hot water or steam to radiators disposed about the building. The fuel 15 for such heaters is often a fluid, such as a low grade oil, or natural or artificial gas.

The flame in the heater has heretofore passed through a nest of tubes, either straight or curved, connected between two headers. 20 In some constructions the flames pass upwardly through a metallic drum in which the heated water circulates. Where tubes are utilized difficulty is experienced in joining the pipes of different lengths and shapes to 25 the headers. An expensive welding, beading or threading operation is necessary. Where cylindrical drums are utilized, an imperfection in any part of the drum renders the whole drum unfit for use.

30 Provision has heretofore been made for regulating the amount of fuel supplied to the heater in accordance with the condition of the water or steam being delivered by the heater. Such regulating systems have not 35 taken into account the chilling effect of the air draft through the heater after the flame has been reduced or extinguished. The draft of air continues to pass through the heater and chills the metal with which it comes in

40 contact to a temperature below that of other parts of the heater and the fluid contained therein. By the time that the temperature of the fluid has been reduced sufficiently to cause the flame to be increased or relit, the 45 metal of the flue has been so chilled that an appreciable period of time elapses before it is again heated to a value such as to transmit heat to the fluid engaging it. This loss of time or lag results in a delay in restoring the 50 fluid to the temperature at which it is desired

to maintain it for uniform heating of the building.

I provide a heater in which the tubes and headers are cast integral and in sections. The sections are assembled in superimposed 55 relation. Clamping means are provided for holding the sections together and permitting the replacement of a defective section without the necessity of discarding other sections. Threaded, or welded joints between the sec- 60 tions are eliminated.

The sections are preferably placed in a sloping position, departing a few degrees from the horizontal, although it is to be understood that for certain purposes the 65 sections can be mounted in a vertical position.

In order to insure that the flames and heated gases shall transmit thermal energy to the sections by convection rather than by radiation, the openings in the sections between the tubes are staggered in both longitudinal and transverse directions. Transverse movement of the gases and flames between the sections is secured by providing alternate sections with different numbers of tubes. The spaces between the tubes are filled with metallic webs in which openings are formed. Preferably one section is provided with one more tube than the sections at each side of it. 70 Accordingly, the gases in traversing the superimposed sections follow a zig-zag course through the heater, thereby increasing the area of heat transfer and the speed of heating the water. Movement of the gases and 75 flames longitudinally of the sections is secured by placing the opening in the webs of adjacent sections in staggered relation.

To prevent a period of lag between the lighting or increasing of the flame in the 80 heater and the period when the increase in thermal energy becomes effective upon the liquid in the heater, I provide means for closing the air vent or vents at the bottom of the heater when the supply of fuel is curtailed. 85 The construction and disposition of the sections is such as to expose a large volume of liquid to the heating action of the gases, thereby increasing the rapidity with which 90 the liquid is heated.

I have also provided improvements in certain of the details of construction of the heater which are hereinafter more fully explained.

5 The accompanying drawings illustrate certain preferred embodiments of the invention in which

10 Figure 1 is a longitudinal side elevational view of a heater embodying my invention with the outer casing removed,

Figure 2 is a front view of the heater,

Figure 3 is a rear view thereof,

15 Figure 4 is a front view of the heater with the casing removed taken along section line IV—IV of Figure 1,

Figure 5 is a plan view of the heater taken along the section line V—V of Figure 1,

20 Figure 6 is a sectional view of a modified form of the heater with the casing removed, the sections being taken along a line corresponding to the section line of Figure 4,

Figure 7 is a sectional view of a portion of the heater shown in Figure 6, corresponding to the section shown in Figure 1,

25 Figure 8 is a longitudinal sectional view through the heating sections showing the arrangement of openings for securing a zig-zag movement of gases and flames longitudinal of the sections,

30 Figure 9 is a transverse sectional view on an enlarged scale of the heating sections taken substantially along the section line IX—IX of Figure 8,

35 Figure 10 is a plan view of one heating section,

Figure 11 is a plan view of another heating section,

40 Figure 12 is a plan view of a modified form of the invention in which a plurality of heating units are connected in side-by-side relation,

Figure 13 is an enlarged sectional detail view of the damper, and

45 Figure 14 is a sectional detail view on an enlarged scale of a portion of the insulating lining.

50 Referring to Figures 1, 2, 3, 4 and 5, a heater embodying one form of my invention is illustrated. The heater is adapted for use with different types of liquid. For heating houses and stores, it is customary to pass water through the heater. The water may be circulated to remotely disposed radiators at a temperature slightly below its boiling point, where hot water heating systems are used. The heater may also be used to generate low pressure steam for transmission to the radiators if a steam heating system is utilized in conjunction with the heater.

55 60 The heater comprises a cast iron base 4 in which a combustion chamber 5 is formed. Burners 6 are mounted in the combustion chamber. The burners 6 may be of different forms although I prefer to use an elongated double tube burner having a large number

of openings 7 along its upper surface. The burners are connected to mixing valves 8 mounted externally of the casing 4. Pipe connections between the mixing valves 8 and the burners 6 extend through supporting 70 openings 9 in the front wall of the base 4. The burners are also supported substantially at their mid-points by rods 10 extending transversely of the heater.

65 The mixing valves are connected to a common header 11. Pilot lights 12 are disposed between the burners 6 and are connected to a feeder pipe 14 running along the front face of the base 4. An escape pipe 15, hereinafter more fully described, terminates adjacent one 80 of the pilot lights 12.

70 The top of the base 4 is provided with flanges 16 for securing a housing thereto. Openings 17 are provided for clamping bolts 18. Openings 19 directly over the burners 6 85 extend substantially the entire length of the base 4 for permitting the escape of flames and hot gases into the heating sections disposed above the base. The bottom of the base is provided with legs 20 that space a plate 21 90 defining the bottom of the combustion chamber 5 a distance from the floor. The plate 21 rests upon flanges 22 formed in the base 4.

75 Referring particularly to Figure 5, longitudinally extending openings 24 are formed in the plate 21 beneath the burners 6. During the burning operation a draft of air is permitted to enter the combustion chamber 5 through the openings 24 for supplementing the air supplied by the mixing valves 8. 100

80 If desired, closure plates 26, shown in Figures 1, 4 and 6, may be placed between the edges of the burners 6 and the inner walls of the base 4 to insure that the air entering the combustion chamber through the openings 24 passes through the openings between the columns of the several burners 6. If the draft traversing the openings 24 is not curtailed when the supply of fuel to the burners 6 is reduced, as hereinafter more fully described, the draft continues to pass upwardly through the heating sections and chills the surface of the metal to a temperature below that at which the fluid in the heater is to be maintained. 110

85 90 When the burners are again ignited or supplied with more fuel, an appreciable amount of time is lost in heating up the chilled metal before the additional heat acts upon the fluid in the heater. To prevent the occurrence of such a heat lag in the heater, the openings 24 are automatically closed by dampers 25 when the supply of fuel to the burners is reduced. For this purpose the dampers 25 are carried on rods 25a extending longitudinally of the base 4 and supported by straps 27 mounted on the plate 21. Straps 28 attach the dampers. The rods 25a extend through the back wall of the casing and are provided with crank arms hereinafter described. 120

There are two shapes of heating sections utilized in each heating unit. Referring to Figure 10, a heating section 29 comprises a plurality of columns or tubes 30 separated by metallic webs 31. By way of illustration and not by way of limitation, the section 29 is shown as having five tubes and four webs. The tubes 30 terminate in a header 32 having a nipple receiving opening 34 formed therein. The nipple receiving openings 34 are of the conventional shape common to radiators for the reception of connecting nipples. Perforated ears 35 are formed at the corners of the section for the reception of the bolts 18. Projections 36 are formed along the outer edges of the section for laterally connecting adjacent sections as hereinafter described. Elongated openings 37 are formed centrally of each of the webs 31. The section 29 is made by casting, thereby eliminating the necessity of connecting the tubes 30 to the headers 32 by any sort of joint.

Referring to Figure 11, heating sections 40 having a different number of tubes 41 than the sections 29 are provided for insertion between the sections 29 in the assembled heater unit. By way of illustration, the sections 40 are shown as being provided with four tubes. The spaces between the tubes are filled with webs 42 similar to the webs 31. However, openings 44 are placed near the ends of the webs rather than at the center, as in the sections 29. Headers 45 are provided for the tubes 41. The headers 45 are provided with nipple receiving openings 46 similar to the openings 34. The sections 40 are not provided with ears for the reception of the clamping rods.

In assembling a heater unit, the sections 29 and 40 are mounted in a sloping position departing from the horizontal by a few degrees. The sections 29 and 40 are arranged alternately. Pipe nipples are placed between the openings 34 and 46, and all are pressed together in large presses. The slip connection thus formed prevents the necessity of threaded or welded joints and permits the ready separation of the sections should it be desirable to separate them for repair purposes. The clamping rods 18 are then passed through the ears 35 and seated in the openings 17. Nuts 47 are then drawn down on the ears 35 of the upper section 29.

Due to the fact that the sections 29 and 40 have different numbers of tubes, the gases traversing the heating section are caused to move laterally of the different sections as illustrated by the arrows in Figure 9. By reason of the staggered disposition of the openings 37 and 44 of the sections 29 and 41, respectively, the gases are also caused to follow a zig-zag course longitudinally of the heating unit, as shown by arrows in Figure 8. As a result of the zig-zag movement of the gases and flames laterally and longitudinally of

each heating unit, the gases are substantially all brought into direct contact with substantially all of the surfaces of the different sections, thereby increasing the volume of liquid exposed to the heated gases and the rate of heat exchange. 70

Fluid is supplied to the lowest section 29 of the heating unit by a pipe 48. Due to the angular disposition of the sections 29 and 40, there is a tendency for part of the heated fluid to flow longitudinally of each section. The fluid moves from section to section through the nipple connections at the ends thereof. 75

The heating units constituted by the alternately arranged sections 29 and 40 may be spaced side-by-side as shown in Figures 4 and 12, or they may be used singly as shown in Figure 6. Where the sections are placed side-by-side, the projections 36 between the edges of the adjacent sections 29 may be opened to permit fluid communication, if desired. 80

As shown in Figure 12, the heating units may also be arranged to abut end-to-end. It is to be understood that by multiplying the connections shown in Figure 12, the width of the heater may be increased as well as its length by simply connecting up more heating sections. 90

A cast iron dome 49 is placed at the top of the sections where a plurality of heating units are placed side-by-side. Nuts 50 at the upper ends of the clamping bolts 18 rest in seats 51 formed in the dome 49, as shown in Figures 1 and 8. Nipple receiving seats 52 are provided at the bottom of the dome for connection with the openings in the upper section of the heater unit. By drawing down the nuts 50, the dome is firmly attached by the bolts 18 to the heater units constituted by the superimposed sections 29 and 40. 95 While I have shown the sections 29 and 40 disposed in substantially horizontal positions, it is to be understood that for certain purposes they may be assembled in substantially vertical positions. 100

The dome is provided with an internal stack 57 for removing the products of combustion from the heating units. A discharge pipe 58 for the dome 49 communicates with radiators or other devices not shown. 115

A relief valve 59 is provided on the dome. A pressure gauge 60 is provided at the front face of the drum, and a water gauge 61 is carried by the front wall of the dome. A fuel regulator 62 is connected with the fluid in the dome 49. Where steam is generated in the heater, the regulator 62 is operated by pressure. Where hot water only is utilized the regulator 62 may operate on other thermal responsive principles. In either case the function of the regulator 62 is to curtail the supply of fuel to the burners 6 if the temperature of the fluid in the drum becomes excessive. In the case of steam, the temperature 120

ture of the fluid is indicated by the steam pressure.

Referring to Figure 6, where a single width heating unit is utilized, a cylindrical tank or boiler 64 is mounted on top of the heating sections in lieu of the cast dome shown in the other modifications of the invention.

The ends of the cylindrical boiler are closed by plates 54 welded thereto. As shown in Figure 7, the plates 54 extend beyond the top of the boiler 64 and have inwardly extending flanges 55. The flanges 55 are utilized for supporting insulating material hereinafter described. Spaces 56 are provided for the passage of gases between the bottom of the plates 54 and the outer ends of the sections. If necessary the plates 54 may be recessed below the bottom of the boiler 64 to provide the spaces. The heated gas and products of combustion pass around the boiler to the stack 64a instead of passing through the boiler, as in the case of the cast dome structure and in this manner the boiler is heated exteriorly over a greater area than in the case of the former.

The entire heating unit is covered by a heat insulating lining. The outer surface of the lining is constituted by sheet metal 65 extending all the way around the heating unit except over the base 4. The sheet metal 65 is inserted within the flanges 16 of the base 4. Within the sheet metal lining 65 there is a layer 66 of laminated asbestos. The asbestos is laminated in a plurality of directions to provide air cells therein. Inside the asbestos layer 66 there is a layer 67 of asbestos board. The layer 66 bears directly against the ears 35, thereby enclosing the heater. The insulating lining at the top of the heater in which the cast dome is employed rests directly on the dome, and in the modified form in which the boiler is employed the lining is spaced therefrom and rests on the flanges 55, as shown in Figure 7.

The connections between the regulator 62 and the burners, pilot and vent lights are shown in Figures 3 and 5. Where gas is used as a fuel, a pressure regulator 70 is provided in a gas main for supplying gas at a definite pressure to the heater.

The pressure regulator 70 is connected to the header 11 by a pipe line 71. A valve 72 is interposed in the line 71. The valve 72 has a counterweighted valve operating lever 72a which is connected by a chain 73 to one end of a lever 74. The other end of the lever 74 is provided with a weight 75 against which a plunger 76 on the regulator 62 operates for turning the lever 74 about a fulcrum 77. The plunger 76 constitutes an element of the regulator 62. Accordingly, when the plunger 76 is raised either by steam pressure in the regulator 62 or by the operation of some other form of thermal responsive device, the lever

74 is moved in a counter clockwise direction, as shown in Figure 3, to close the valve 72, thereby cutting off or reducing the supply of fuel to the burners 6. When the pressure exerted by the plunger 76 decreases, the lever 74 is turned in a clockwise direction by the weight 75 to again open the valve 72.

For operating the dampers 25 simultaneously with the valve 72, a rod 80 is connected to the lever 74. The rod 80 is connected to one arm of a bell crank 81 mounted on one of the rods 26. The other arm of the bell crank 81 is connected by a link 82 to an arm 83 on an adjacent rod 26. The number of rods 25a controlled by the bell cranks 81 may be varied as desired by simply increasing the number of connecting links 82. Upon the depression of the end of lever 74, the bell crank 81 is turned. The turning movement is transmitted to the connecting rods 25a for turning them to close the associated dampers. Upon the end of the lever 74 being again raised, the cranks are rotated to open the dampers 25.

The pilot lights 12 are connected by a pipe line 90 to the pipe line 71 behind the valve 72, thereby insuring a continuous supply of fuel to the pilot lights independently of the operation of the valve 72. The vent pipe 15 is directly connected to the pressure regulator 70 for permitting the escape of gas therefrom and conveying the escaped gas to a pilot light where it is consumed, rather than being liberated in the building.

While I have shown and described the present preferred embodiment, it is to be understood that it may be otherwise embodied without departing from the spirit of the invention or the scope of the appended claims.

I claim:

1. A heating device comprising a plurality of sections, each section comprising a plurality of parallel tubes and connecting webs between and running with the tubes, said webs having openings formed therein.

2. A heating device comprising a plurality of sections, each section comprising a plurality of parallel tubes and connecting webs between and running with the tubes, said webs having openings formed therein, and the openings in successive webs being arranged in staggered relation.

3. A heating device comprising a plurality of horizontally extending sections, each section comprising a plurality of parallel tubes and connecting webs between and running with the tubes, said webs having openings formed therein, the openings in said webs being staggered longitudinally of the sections.

4. A heating device comprising a plurality of sections, each section comprising a plurality of tubes and connecting webs having openings formed therein, the tubes in successive sections being offset in one direction and openings in the webs being offset in another

direction, whereby a column of gas traversing the heater is caused to vary its movement in a plurality of directions.

5. A heating device comprising a plurality of sections, each section comprising tubes and connecting webs having openings therein, the tubes in adjacent sections being offset laterally of the heating device, and the openings in adjacent sections being offset longitudinally of the heating device.

10. A unit for a heater, comprising an integral section having header portions formed in the ends thereof with openings for fluid connections, parallel tubular portions connecting the header portions, and horizontal perforated webs running with and connecting the tubular portions.

15. A unitary section for a heater, comprising header portions, parallel tubular portions connecting the header portions, horizontal perforated webs running with and connecting the tubular portions, and projecting portions on certain of the tubular portions for providing fluid communication with another section 20 adjacent one edge thereof.

25. In testimony whereof I have hereunto set my hand.

THOMAS E. LANDVOIGT.
